UNITED STATES PATENT OFFICE.

FRED C. FANTZ, OF ST. LOUIS, MISSOURI, AND ESTES G. RATHBONE, OF TACOMA, WASHINGTON, ASSIGNORS TO THE TEXAS COMPANY, OF NEW YORK, N. Y., A CORPORATION OF TEXAS.

PROCESS OF MIXING WOOL WASTE AND GREASE.

Application filed November 17, 1919. Serial No. 338,639.

To all whom it may concern:

Be it known that we, FRED C. FANTZ, a citizen of the United States of America, and a resident of St. Louis, St. Louis County, 5 and State of Missouri, and ESTES G. RATHBONE, a citizen of the United States of America, and a resident of Tacoma, Pierce County, and State of Washington, have invented certain new and useful Improvements in Processes of Mixing Wool Waste 10 and Grease, of which the following is a specification, reference being had to the accompanying drawing, forming a part thereof.

15 Our invention relates to the mixing of very viscous liquid or semi-solid material such as grease with fibrous materials such as wool waste, and has special reference to the production of what is known as wool waste grease.

One object of our invention is to provide a simple and effective process for thoroughly and expeditiously mixing ingredients of the character above indicated.

20 Another object is to provide a simple and effective apparatus for practicing the aforesaid process on a commercial scale.

The most effective method hitherto known for accomplishing the objective results of 25 our invention consisted in the separation of the wool waste of fibrous material and the spreading of alternate layers of waste and grease in a receptacle or vat where the desired mixture was effected by treading upon 30 the mass.

According to our invention this primitive method is replaced by a rotary mixer having combining prongs or teeth which carry the mass to be mixed for a certain distance 35 up the side of the rotary device and pull the fibres through the grease to a greater or less extent, before the mass is allowed to fall off of the teeth or prongs.

In order that our invention may be 40 thoroughly understood we will now proceed to describe the same in the following specification and will then point out the novel features thereof in appended claims.

Referring to the drawings:

45 Figure 1 is a sectional elevation of a mixer arranged and constructed in accordance with

our invention and adapted for practicing our improved process.

Figure 2 is a partial sectional elevation of the same device. 55

In the drawings, 10 designates a frame on which two pairs of spaced rollers 11-11 and 12-12 are mounted. These rollers constitute supports for a cylindrical container or mixing drum 13 having annular projections or ribs 14-15 which respectively engage the rollers 11-11 and 12-12. The drum is provided with a driving gear 16 which meshes with a pinion 17 affixed to a driving shaft 18. 60

The drum is provided with any suitable gate or opening 19 which, in the arrangement illustrated, is pivoted at 20. The interior walls of the mixer are provided with a plurality of teeth or fingers 21 which extend inwardly in a radial direction but are preferably curved or hooked to a slight extent in the direction of rotation. In order to obtain the best results the fingers 21 are arranged in a staggered relation as shown in 65 the drawing. 70

In performing the mixing operation the proper proportions of separated wool waste, or other suitable fibre, and grease, or other material of similar characteristics, which it 75 is desired to mix, are introduced into the mixing drum 13. The drum is then rotated in the direction of the arrow in Figure 1 with the result that the mass of grease and waste is not only rotated with the drum, but is also shredded or combed by the teeth or 80 projections. 85

Attention is directed to the fact that the mass is subjected to a kneading action by being carried up the sides of the mixer as 90 it is rotated and dropped or rolled together simultaneously with the shredding or combing action.

It is found that this process and apparatus are particularly well adapted for the 95 purpose described and that large quantities of wool waste grease may be mixed in a very short time at a great saving over the previously known methods.

100 Ordinary mixing processes and apparatus are absolutely unsuited for this purpose, because either the fibrous material is not prop-

erly intermingled with the grease, or, if stirrers, paddles or other devices of like character are employed, they merely gather up a greater and greater mass of fibres and separate them out of the grease and clog the stirring mechanism instead of mixing them as desired.

Apparatus of preferred form and construction have been illustrated and described for the purpose of showing a way in which this invention may be used, but the inventive thought upon which this application is based, is broader than these illustrative embodiments thereof, and we therefore intend no limitations other than those imposed by appended claims.

What we claim is:

1. The process of impregnating a fibrous carrier with a grease component which consists in mixing said carrier and grease com-

ponent together with a rotary motion while at the same time subjecting the mass to a shredding or combing action.

2. The process of impregnating fibrous waste material with grease which comprises physically mixing the two components by first introducing the required quantity of waste material and grease into a cylinder having inwardly projecting teeth, then revolving the cylinder so that the teeth successively raise the waste and subsequently drop it back upon the body of grease until the waste material has become thoroughly impregnated with the grease.

In witness whereof, I have hereunto set my hand this 27th day of October, 1919.

FRED C. FANTZ.

In witness whereof, I have hereunto set my hand this 4th day of November, 1919.

ESTES G. RATHBONE.
